BOTTLE HOLDER

Henry K. Powell, Chicago, Ill., assignor to Morris Paper Mills, Chicago, Ill., a corporation of Illinois

Application May 5, 1938, Serial No. 206,126

3 Claims. (Cl. 229—31)

This invention relates to receptacles for the packaging of a plurality of bottles or the like in a fashion such as to facilitate their being carried.

The general object of the present invention is the provision of such a holder which may be manufactured very economically of suitable sheet material, such as paper board, and which will constitute a sufficiently strong and stable container or holder for the intended purpose, and be effective to retain the bottles securely against dropping out, yet permit them to be inserted into it readily, and as easily removed, by proper procedure.

One of the objects is to provide such a carrier which is adapted to be supplied to the user in flat or knocked-down condition and to be readily set up by the user, preliminary to placing the bottles in it, without requiring any special apparatus or any additional fastenings for assembling it or securing it in set-up condition.

Another object is the provision of such a holder which will retain its set-up form whether or not bottles are within it, and thus continue to serve as a convenient repository for the empty bottles.

A particular object of the present invention is the provision of such a carrier which may be made from flat sheet stock and equipped with an efficient handle whereby it may be carried, and which includes features whereby the handle is afforded additional security of connection and the parts of the receptacle which are particularly subjected to stress from the weight of the contents when carried by the handle are effectively strengthened and reinforced.

Yet another object is the provision of a novel construction for a carrier of the type above referred to, wherein a single sheet affords a tray-like bottom portion which may be set up from a flat condition, and suitable retaining and supporting walls whereby the tray-like portion is retained in set-up form and is suspended on the handle.

Other and further objects of the invention will be pointed out or indicated hereinafter, or will be apparent from the ensuing description or upon actual use of the invention.

In the accompanying drawings forming a part of this specification I show, and hereinafter describe, certain embodiments of the invention. It is to be understood, however, that these are presented merely for purpose of illustration and are not to be construed in any fashion calculated to limit the appended claims short of the

true and most comprehensive scope of the invention in the art.

In said drawings,

5 Fig. 1 is a perspective view of a bottle holder embodying the present invention, showing the same in set-up condition;

Fig. 2 is a plan view of the blank from which the same is formed, showing the blank as originally cut from the sheet;

10 Fig. 3 is another view of the blank showing it in a form in which it is shipped to the user, certain of the portions illustrated in Fig. 2 having been folded over upon others and glued in position;

15 Fig. 4 is a detail in the nature of a perspective, viewing from below one end of the top of the holder shown in Fig. 1;

Fig. 5 is a detail in the nature of a perspective of a portion of the top of a holder of a modified form, equipped with a type of handle differing in certain particulars from that illustrated in Figs. 1 and 4; and

Fig. 6, is a perspective view of a modified construction.

20 25 The nature of the invention will be most quickly ascertained from a detailed description of the embodiments shown in the drawings, as follows.

The receptacle portion of the holder is formed 30 from a sheet of paper board or the like, having the proper strength and stiffness, a blank of the form shown in Fig. 2 being cut from such sheet. This blank is apportioned by slots and scored crease lines into the following parts, viz., a bottom panel 10 conjoined along crease line *a* with side panel 11, the upper portion of which is slotted on lines *b* to form a tab 12 having along one margin a fold crease *c*. Side panel 11 is conjoined to a second side panel 11' along a top crease line *d* and said second side panel 11' is slotted along lines *b* to provide a tab 12' having a fold crease *c'*. Side panels 11 and 11' are also provided with fold creases *e*. At the outer margin of side panel 11' is formed a connecting member comprising a pair of locking tongues 14, whose limits are defined by a fold crease *f*, and bottom panel 10 is provided with a slot 15 for interlocking engagement with said locking tongues. It will be observed that the locking tongues are severed along a line *g* so that they may be overlapped one upon the other and their hooked portions moved closer together, thus to permit their introduction through the slot 15, which is long enough to accommodate 50 55 only the narrower portions of said tongues at

the end of their locking notches when the tongues are in abutment with each other along the line *g*.

The bottom panel *10* is conjoined to a side wall strip *16* along a fold crease *h*, and to end strips *17* and *18* along fold creases *i* and *j*. Said end strips *17* and *18* partially overlap the side panel *11*, and along the opposite end margins of said panels *11* and *11'* are formed margin strips *20* and *21*, having extensions *20a* and *21a* adjacent the fold line *d*. Slots are formed in the margin strips as indicated at *22*, and handle holes *24* are punched in it in alignment therewith on the fold crease *d*. The diagonal fold creases *k* are formed in the end portions of end strips *17* and *18*.

The end strips *17* and *18* and margin strips *20* and *21* are folded inwardly upon the adjacent portions of the bottom panel and side panels, and fastened flat against them by glue or other suitable adhesive which is applied between them in the areas designated by stippling in Fig. 3. This completes the forming of the body member of the holder, and it is in this flat form that it is stacked and shipped to the user.

A wire handle is provided, same comprising a bail portion *26* having at its ends journal portions *27* which are in alignment with each other and extend toward each other. The proximate ends of these journal portions *27* are closer together than are the handle holes *24*, said holes being at a distance corresponding to the spacing of the outer extremities of said journal portions *27*.

Accordingly, to set up the holder, the user first inverts it from the position shown in Fig. 3, and then bows or flexes it along its longitudinal axis sufficiently to bring the handle holes *24* close enough together to permit the ends of the handle journals *27* to be inserted through them. Then, upon releasing the bowed sheet, it springs back to the flat form, thereby securely locking the handle to it. It will thus be seen that the journal portions *27* of the handle rest against the under sides of the extensions *20a* and *21a*, below the top crease line *d*.

Continuing with the setting-up operation, the operator folds the side panels toward each other along crease line *d*, in the direction away from the handle bail, and flexes the tongues *14* on the crease line *f* in the same direction. Then grasping the free margins of the end strips *17*, he draws them apart, whereby they bend along the diagonal lines *k*, and flexes the side strips *16* inwardly on line *h* and bottom panel *10* toward side panel *11* on line *a*. Side panel *11'* is then placed against the outer side of side strip *16*, the locking tongues *14* overlapped and swung toward each other and inserted through the slot *15* and then released so that their locking hooks engage the ends of said slot. When this has been completed, the holder has the form shown in Fig. 1, wherein it will be seen that the bottom panel and its strips *16*, *17* and *18* are held in set-up form by virtue of engagement of the side panels *11* and *11'* and the interlocking connection between the bottom panel and side panel *11'*.

The tabs *12* and *12'* may be swung inwardly to the position shown in Fig. 1, thus affording apertures through the upper portions of the side walls for introduction of bottles into the holder. The holder illustrated is designed to receive six bottles in two rows of three each. The first two bottles inserted through each of the side apertures are moved to the ends of the apertures, where they are stopped by abutment against the margins of the apertures and strips *20* and *21* and the third

bottle is inserted between them. The end strips *17* and *18* retain the bottles against sliding off, and the height of the side walls is designed relative to the height of the bottles so that the upper portions of the bottles remain projecting upwardly out of the top apertures. Consequently, the upper portions of the bottles are held against moving apart, and the entire group of bottles is consequently securely retained in the holder.

When carried by the handle bail *26*, the weight is supported by the relatively narrow portions of the side panels which are at the ends of the bottle-receiving apertures. However, these are well adapted to sustain the weight, by virtue of the double thickness of material which is afforded by said portions and the margin strips *20* and *21* which form connections between portions of the side panels above and below the bottle receiving apertures. It will be observed that the inner portions of the extensions *20a* and *21a* are not glued to the body sheet, and that glue is also omitted along the crease lines *e*. This is advisable in that it permits the in-turned margin strips to accommodate themselves to the internal angle of those creases, without unduly stretching the material of the outer sheet at those points. At the same time they effectively reinforce and strengthen the structure in those locations. The angular relationship of the tabs *12* and *12'* to the portions of the sheet to which they are conjoined along the lines *c* and *c'* forms a beam-like structure which effectively strengthens this portion of the holder and forms a stiff strut or stay which effectively resists any tendency of the portion below the handle bail to buckle under the weight of the contents. This relieves the portions at the ends of the bottle apertures of tearing stresses.

In Fig. 5 is illustrated a modified form of handle fitting, which may be employed in a body sheet structure as above described, the body sheet being modified in the particular that instead of having separated handle holes on the crease line *d*, a slit *30* is formed along said crease line intermediate its ends, said slit terminating at the ends of the in-folded projections *20a* and *21a*. The handle comprises a bail portion *31* with leg portions *32* having outwardly jutting kinks or bends *34*, and outwardly projecting journal portions *35*, which are aligned with each other. The leg portions *32* are spaced apart a distance corresponding to the length of the slit *30*. This handle is assembled with the body member by inserting the bail *31* through the slit *30* to the extent permitted by the kinks *34*, then springing the legs together so as to permit the kinks *34* to pass through the slot, then releasing the legs and permitting them to spring back to their normal distance, whereat they engage the ends of the slit, and thus position the journal portions *35* under the margin strip projections *20a* and *21a*. Thus the body of the holder swings on these journals when the holder is supported by the bail of the handle.

It is to be understood that the construction above described may be changed or modified in various particulars without departing from the spirit of the invention. For example, as shown in Fig. 6 both side panels *11* and *11'* may be formed integrally with respective side margins of the bottom panel, thus eliminating the side strip and the interlocking connection between the side and bottom panel. In such case, the end strips, one of which is shown at *27*, are formed and operate as above described and are secured at their ends to both side panels by margin strips

21 in the same fashion as above described, and upper portions of the side panels, as at H, are connected to each other in any suitable fashion and provided with a handle, or merely held together by the hand which grasps the handle.

As in the construction illustrated in Fig. 1, the end strips in the modification shown in Fig. 6, function as stays or struts at the ends of the bottom panel, bracing the lower portions of the wall panels against flexing inwardly and stiffening the bottom panel against flexing under the weight of the container's contents.

Certain constructions herein illustrated or described but not defined in the following claims form subject matter of and are claimed in my copending applications for Bottle holders, Serial Nos. 196,230, filed March 16, 1938, and 271,827, filed May 5, 1939.

What I claim is:

1. In a container of the class described, a sheet of paper board creased to provide a bottom panel having end strips along its ends and a side strip along one side and at its opposite side two side panels arranged end-to-end in series; said end strips being folded inwardly onto the bottom panel and side strip and first side panel and being secured in that folded position by attachment to the side strip and said side panel and creased diagonally over the side strip and side panel to fold away from the bottom panel, whereby the end strips are adapted to be raised to upstanding positions relative to the bottom panel when the side strip and the first side panel are flexed to upstanding positions at the sides thereof; the second side panel having an extension foldable under the bottom panel and engageable therewith to secure said second side panel against the outer surface of the side strip and thereby support said side strip in upstanding position, a handle being provided at the upper ends of the side panels whereby the container may be carried with the bottom panel in horizontal position.

2. A bottle carrier for retaining a plurality of bottles in upstanding position therein, comprising a receptacle formed of paper board and having a bottom of size to accommodate two collaterally disposed rows of the intended bottles standing

upright thereon and side panels connected to the bottom and extending upwardly from opposite side margins thereof and having portions sloping inwardly and upwardly over the bottom and conjoined to each other at their upper ends, said side panels being provided at their upper ends with a handle whereby the receptacle may be suspended and having in their inwardly extending portions bottle-receiving apertures each of a size to accommodate the neck portions of a row of the intended bottles standing upright on the bottom and projecting through said aperture, and margin strips bent inwardly from lateral margins of the side panels and secured against inner surfaces thereof in positions where their inner edges approximately coincide with outer margins of said apertures and they afford lateral abutments for the outermost bottles of the rows, said margin strips constituting load-carrying members connecting portions of the side panels which are below the respective ends of the bottle-receiving apertures with portions of the side panels which are above said respective ends.

3. In a container of the class described, a sheet of paper board creased to provide a bottom panel having end strips along its ends and a side strip along one side and at its opposite side two side panels arranged end-to-end in series, said end strips being folded inwardly onto the bottom panel and side strip and first side panel and being secured in that folded position by attachment to the side strip and first side panel adjacent the bottom panel, said end strips being creased diagonally over said side strip and first side panel to swing away from the bottom panel when the side strip and the first side panel are swung to upstanding positions at the sides thereof, and means for securing the second side panel to the bottom panel in upwardly extending position alongside the side strip where it supports the latter in upstanding position, a handle being provided at the upper ends of the side panels whereby the container may be suspended pendulously with the bottom panel in horizontal position.

45 HENRY K. POWELL.
